UNITED STATES PATENT OFFICE.

HIRAM C. WILLIAMS, OF UTICA, NEW YORK, ASSIGNOR OF ONE-THIRD TO FRANCIS B. HARRINGTON, OF ALBANY, NEW YORK, AND ONE-THIRD TO STEPHEN R. PAYNE, OF SYRACUSE, NEW YORK.

RAILWAY SWITCH AND SIGNAL APPARATUS.

1,151,316.

Specification of Letters Patent. Patented Aug. 24, 1915.

Application filed March 28, 1910. Serial No. 551,915.

To all whom it may concern:

Be it known that I, HIRAM C. WILLIAMS, a citizen of the United States, residing at Utica, in the county of Oneida and State 5 of New York, have invented certain new and useful Improvements in Railway Switch and Signal Apparatus, of which the following is a specification.

My invention relates to railway switch 10 and signal apparatus, and the object of my invention is to provide a switch stand with connecting apparatus whereby the signal may be set and locked, the switch points moved and locked, a derail closed, and all 15 so arranged that the signal cannot be changed until the switch points have been again moved, locked in their new position and the derail opened and locked in its open position, when the signal may be turned 20 showing the track to be clear; together with the elements and combinations hereinafter more particularly set forth and claimed. I accomplish these objects by means of the mechanism illustrated in the accompanying 25 drawings, in which,

Figure 1 is a perspective of the track, showing the connections of my switch stand. Fig. 2 a plan of the switch stand with connections broken away. Fig. 3 a section 30 along the lines V—V on Fig. 2. Fig. 4 a section along the lines W—W on Fig. 2. Fig. 5 a section along the lines X—X on Fig. 2. Fig. 6 a view of the locking bar. Fig. 7 a view of the pinion and shaft connection. Fig. 8 a view of the shaft connection with a signal lever.

Similar letters refer to similar parts throughout the several views.

A represents the main line, B the siding. 40 The switch point, C, is connected with a rod, D, to a lever, E, the movement of the lever, E, causing the switch point, C, to be moved to or from the rail, a, of the track A. The switch point, C, is also connected to a locking rod, F, which is provided with a flattened portion, f, which has two or more openings, g, h, therethrough, and which flattened portion reciprocates through a suitable locking box, G.

50 The lever, E, carries a post, K, which is provided with projections, k, k, which have their extreme ends at an angle to each other as shown in Fig. 2 and with which the sliding block, L, attached to the rack, M, en-

gages in its reciprocation under the direction of said rack and which engagement causes the rotation of the post, K, which will in turn impart a reciprocating movement to the rod, D, which, as before stated, is attached to the switch point, C, and therefore in its movement will open or close the switch point with reference to the rail, a.

Within the locking box, G, I placed the bolts, N and O, adapted to be alternately forced through the openings g, h, in the rod, F. My means for moving the bolts, N and O, preferably consists of the rods, n, o, respectively, connecting different points on the periphery of the wheel, P, on the shaft, R, so arranged that when one of the bolts, N, 65 is forced into one of the openings, g, in the rod, F, the other bolt will be withdrawn out of connection with the rod, F, or its opening, and when the bolt which is in the opening in the rod, F, is withdrawn therefrom 70 the other bolt will be forced into the other opening, h, thereby locking the rod and hence the switch point to which it is attached, in each position, open or closed in reference to the rail, a.

I have shown the two openings, g, h, in the rod, F, in different horizontal planes, because I want to prevent any possibility of the bolt passing through the wrong opening. In case a break should occur, or the rod, F, should fail to move properly because of the switch point neglecting or refusing to move, then the locking bolt will strike the locking rod, F, instead of entering one of the openings therethrough, which would prevent, as will hereinafter be shown, the complete movement of the switch lever and thus not only show clearly to the operator that the switch is not being moved, but will prevent a movement of the signal, which has been set at danger, until this matter of the refusal of the switch point to move has been rectified.

The shaft, R, which has its end, R', squared and upon which squared portion the wheel, P, is keyed, is provided with the rounded portion, R², followed by the squared enlarged portion, R³. On the squared portion, R³, of the shaft, I mount a pinion, s, which meshes with the rack, M. To the 100 rack, M, is attached, as before stated, the block, L, which engages with the projection, k, on the post, K, and to which is attached

the rod, T, which is connected with the bell crank lever, t, one arm of which is connected with the switch point, U, adjoining the derail, U', and by the movement of which the point, U, is brought in contact with or moved from the derail, U'. The movement of the switch lever, S, hereinafter described will therefore control the movement of the rod, D, and the switch point, C, will operate the bolts, N and O, locking the switch points and unlocking them, and will also move the derail switch, U, so as to open and close connection therewith.

On the shaft, R³, adjacent to the rounded portion R², and at the rear end of the squared portion, R', is a beveled gear, Y, which meshes with the beveled gear, Y', on the plate, Y² to which is attached a post, Y³, carrying a signal, Y⁴.

It is understood that the shaft, R', R², R³, is suitably mounted in the casting, 10, and that the post, K, passes through the bottom, 11, of the casting, 10, the lever, E, and rod, D, being beneath the plate, 11. I do not, however, wish to limit myself to this construction of the casting or relative location of the parts in reference to the same.

Adjacent to the end of the shaft, R³ and extending in a prolongation thereof is the shaft R⁴ upon which and mounted in the side, 12, of the casting is the sleeve, 13, squared at the end, 14, and upon which squared end, 14, is secured the signal lever, 15.

On the shaft, R⁴, I mount loosely the commutator, 17, connected to the sleeve, 16, by a clutch, 30, as shown in Figs. 2 and 4. The commutator, 17, is also held in place on the shaft, R⁴, by the pin, r, passing through the collar, r', at the end of the commutator. The commutator, 17, is connected by the wires, 18, with the semaphore, 19, or other suitable signaling apparatus in such a manner that the current from the commutator may be carried to the signal operating apparatus, not shown, by means of which the semaphore may be set at danger or other position as desired, depending upon the position of the commutator. I also connect with the signal lever, 15, by means of a cam-shaped hub, 20, a link, 21, secured to a sleeve, 22, attached to a rod, 23, which rod, 23, has at its end a bolt, 24, passing into a locking box, 25, within which reciprocates bar, 26, attached to the end of the switch point, U, adjacent to the derail, U'. Thus the movement of the signal lever, 15, will set the signal through the current breaker and will lock or unlock the switch point in connection with the derail.

Between the levers, S and 15, and mounted in the side, 12, of the casing is a rocking locking plate, 27, which is provided on each side with a shoulder, 28, 29, which will project over the levers, S and 15, respectively,

depending upon the direction in which the rocking locking plate is inclined and its direction of inclination is controlled by the movement of one of said levers; that is, if signal lever, 15, is raised from the position occupied by it, as shown in Fig. 2, the rocking locking plate, 27, must be inclined toward and the shoulder 28, project over switch lever, S, in order to allow signal lever, 15, to pass the shoulder, 29. It cannot be raised for the purpose of setting the signal at "danger" without thus locking and holding locked the switch lever, S, until the signal lever movement is completed.

In order to move the switch lever, S, the rocking locking plate, 27, must be pressed over upon signal lever, 15, so that it cannot be moved until the switch lever, S, has moved the switch points and also the derail switch. It is apparent therefore that the danger signal cannot be changed until the switch lever, S, has again been moved, clearing the main track from connection with the switch points and opening the derail by separating the switch point, U, therefrom and completing its movement by being laid in the casting, thereby permitting the locking bar to rock over it and release the signal lever, 15, which may then be raised and projected through its course, changing the signal to "clear" and locking the derail switch point, thereby insuring absolute protection from anything running onto the main track from the siding while the signal shows the track to be free or clear.

It will be understood that by arranging the projections, k, on the post, K, in the manner illustrated and described, the block, L, operating in connection with said projections will be capable of a certain amount of lost motion during its movements in connection therewith, which will permit the bolts, N and O, connected with the shaft by means of the wheel, P, to be operated upon and therefore withdrawn from the locking bar before the movement of the switch point is attempted.

The connection between the signal lever, 15, and the sleeve, 22, connected with the derail locking rod, 23, permits of a movement of the rod whereby the derail will be locked only when the "clear" signal is displayed.

With my arrangement of the operating levers, the switch lever and the signal lever, they are moved through an angle of substantially 180° and are placed parallel to the track, thereby making my switch stand one that can be used where there is no more space for the switch stand and connections than that between two tracks. It can also be used at a distance from the track.

A further noticeable feature of my invention is that the derail is operated at the switch stand but with a movement of 6" or 120°

more, whereby a direct and positive motion is given derail lock and switch.

The circuit breaker controller or commutator, 17, is a device for electrically displaying a signal, as at semaphore, 19, or any other predetermined signal, and the electrical controller may be connected up in any suitable manner, not shown.

What I claim as my invention and desire 10 to secure by Letters Patent, is:

1. The combination of a switch; a derail; and a signal; with a switch stand, comprising a lever for moving said switch; means set in motion by the movement of said lever 15 for moving the derail; a lever for moving the signal; means set in motion by said signal lever for locking and unlocking said derail; means for locking the switch point; means for locking said levers preventing the 20 movement of the switch point and derail operating means during the movement and until the completion of the movement of the signal operating mechanism, and then holding the signal mechanism and the derail

locked until the mechanism for operating 25 the switch has closed the same.

2. The combination of a switch; a derail; and a signal; with a switch stand, comprising a lever for operating the switch; a lever for operating the signal; a rod adapted to 30 be attached to the switch point; means operated by the switch lever operating said rod; a rod adapted to be connected to the derail; means connecting said derail rod with the means operated by said switch 35 lever for reciprocating the derail rod and the switch point simultaneously; a rod adapted to lock the derail; means put in motion by said signal lever for operating the derail locking rod; and means connecting said derail locking rod with said last mentioned means.

In testimony whereof I have affixed my signature in presence of two witnesses.

HIRAM C. WILLIAMS.
